WELL CLEANOUT TOOL

James C. Smith and James S. Taylor, Tulsa,
Okla., assignors to Iverson Tool Company,
Tulsa, Okla., a corporation of Oklahoma

Application May 18, 1934, Serial No. 726,364

13 Claims. (Cl. 166—19)

The invention relates to well cleanout tools, and has for its object to provide a device of this kind adapted to be lowered into the well, and provided with means whereby when it reaches the bottom of the well, débris in the bottom of the well will enter the device so that it may be removed from the well.

A further object is to provide a hydrostatic cleanout tool, particularly adapted for use in connection with oil wells and adapted to be extended to the bottom of the well and provided with a chamber normally closed during the lowering operation by a closure held by tripping mechanism and opened by engagement with the bottom of the well to be pushed up into the chamber by hydrostatic pressure, for removal purposes.

A further object is to provide the tool with an upper and lower chamber the upper one of which is provided with a suction plunger and adapted to complete the filling operating in case the hydrostatic action partially fails.

A further object is to so construct the suction plunger that it forms a set of jars for jarring the tool out of the débris, should it become stuck.

25 A further object is to provide a cleanout tool for wells comprising an elongated body having two chambers therein, in one of which a hydrostatic plunger is slidably mounted and adapted to be released for upward movement when the device reaches the bottom of the well, and means for trapping the débris in the hydrostatic chamber after the upward movement of the plunger.

30 A further object is to provide the lower end of the lower chamber with removable and interchangeable ends to meet the various cleaning out conditions.

35 A further object is to provide the lower end of the hydrostatic plunger with an extension extending below the lower end of the cleanout device and adapted to engage the bottom of the well and latching means cooperating with the downwardly extending member and holding the plunger against upward movement until the latching means is released or tripped.

40 A further object is to provide means whereby the hydrostatic plunger may be completely removed from the tool, permitting the tool to be used as a suction device only.

45 A further object is to provide the hydrostatic plunger with downwardly extending pivoted arms having heads extending into recesses in the lower chamber wall and held therein by an enlargement carried by the downwardly extending plunger member, which has limited axial move-

ment in relation to the plunger for moving the head from between the arm enlargements.

A further object is to provide a hinged closure within the chamber and adapted to close the lower end of the chamber when the plunger unit 5 moves upwardly after a débris intaking operation.

A further object is to provide a check valve and discharge port in the extreme upper end of the tool for allowing escape of air, which is at 10 atmospheric pressure, until tripped under the force of the hydrostatic pressure upwardly into the chamber on an intaking operation.

A further object is to provide the upper chamber with an extension member carried 15 therein and having a suction plunger thereon and adapted for use under a vacuum lifting system for cleaning the lower end of the well, by a pumping operation.

A further object is to provide a cleanout tool 20 to be operated hydrostatically or by suction, or by a combination of both.

A further object is to provide the flap valve with means whereby during the clearing and cleaning operation of the device, it may be 25 opened outwardly, thereby obviating the necessity of removing the end of the device.

A further object is to provide a cleaning out bit having a chamber therein with an impact cutting edge having a transverse chamber there- 30 through in which is hinged mounted a flap valve, the free end of which is supported on a removable member thereby allowing the valve to swing outwardly through the bit opening to an open position for discharging the contents of the 35 chamber.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a vertical transverse sectional view through the bottom of the cleanout tool, showing the same in latched position for lowering into a well.

Figure 2 is a view similar to Figure 1, but showing the initial unlatching position.

Figure 3 is a vertical transverse sectional view through the suction chamber and an extension member, adapted to be attached to the upper end of the hydrostatic chamber and used, when it is 55

desired for pumping material into the chambers.

Figure 4 is a perspective view of the bit with a cutting edge, used for breaking up material, where the pieces are large.

5 Figure 5 is a vertical transverse sectional view through the bit shown in Figure 4 having a cutting edge where it is necessary to break up material at the bottom of the well.

10 Figure 6 is a perspective view of another form of bottom to be used with or without the hydrostatic arrangement.

15 Referring to the drawing, and particularly to Figures 1 and 2, the numeral 1 designates a coupling, which coupling is provided with a port 2 extending therethrough, and to which coupling is connected a cylindrical body 3 having an elongated débris receiving chamber 4 therein, and into which broken rock and other débris in the 20 bottom of the well is forced by hydrostatic pressure when the cleanout tool reaches the bottom of the well and engages the débris.

25 Removably mounted on the lower end of the cylindrical body 3 is a chambered member 5, in which is slidably guided the enlarged portion 6 of the axially movable shaft 7 carried by the piston 8, which is in turn slidably mounted in the chamber 4. Shaft 7 extends through an aperture 9 in the bottom of the piston and terminates in a nut 10 having limited movement axially between the rubber bumper 11 within the chamber 11a of the piston and the bottom of the chamber. The rubber bumpers 11 are provided to take up the shock incident to the operation of the device, under terrific pressure.

30 It is also necessary to provide the bumpers 11 and limited movement of the shaft 7 for the unlatching operation. The latching means comprises downwardly extending links 12, which are pivotally connected at 13 to the lower end of the piston 8, and which links terminate at their lower end in enlargements 14, within the chamber 15 of the removable lower end 5 of the device. The enlargements 14 are received in recesses 16 in opposite sides of the chamber 15, and are normally held therein by the enlarged portion 17 carried by the shaft, thereby positively holding the piston 8 against upward movement until the shaft 7 is forced upwardly by the engagement of the eye 18, carried by the lower end of the shaft, 35 with the bottom of the well. It will be noted that the enlargement 6 is smaller than the chamber 15, thereby allowing free movement through the chamber. The eye 18 is used to receive a tool for pulling the piston to lower position for a 40 resetting operation, and its use will be obvious when it is considered that the chamber 4 is ordinarily about thirty feet long.

45 When the eye 18 engages the bottom of the well, the shaft enlargement 17 is moved upwardly to a position above the link enlargements 14, thereby allowing said link enlargements, which have bevelled engagement at 19 with the recess 16, to move upwardly with the piston 8 under hydrostatic pressure, and as the piston 8 is working against atmospheric pressure in the chambers, it is obvious that a terrific inrush will be created below the piston which will take the débris in the bottom of the well.

50 During the débris intaking operation, when the piston 8 is forced upwardly under terrific hydrostatic pressure, the air within the chambers is held at atmospheric pressure by a check valve 20 against which the hydrostatic pressure acts, through the apertures 21 in the tool joint connector 22. Valve 20 is forced upwardly

5 through ports 2 and 41 unseating check valve 20 and thence to the well through the aperture 21. After the piston, to which the arms 12 are connected, reaches the upward position and the débris is moved into the lower end of the chamber, said débris is held trapped in the chamber for removal purposes by a hinged valve 23, which is hingedly connected at 24 to the upper end of the removable lower end 5, hence when the cleanout tool is removed from the well the débris 10 will be removed therewith. When the cleanout tool is cleaned, it is only necessary to remove the lower end 5 from the cleanout tool to remove the débris from the chamber 4, then replace lower end 5 and insert a tool into hooked engagement 15 with the eye 18 to reset and latch the piston 8 for any subsequent operations desired.

10 The lower end of the port 2 in the coupling 1 terminates in an enlarged chamber 25 which receives the nut 26 carried by the upper end of the piston 3 when the piston is in upper position. The nut holds a bumper plate 27 on the piston and the rubber bumper 28 carried by the upper end of the piston in position. The rubber 28 is provided to take up the impact of the piston against 25 the upper end of the chamber 24 at 29, under the terrific hydrostatic pressure.

15 The piston 8 is provided with inverted cup shaped packings 30, against which the hydrostatic pressure from below the piston acts for maintaining the atmospheric pressure in the chamber 4. In a five thousand foot well, the hydrostatic pressure, per square inch would be about 2,110 pounds, if the hole is full of water, and it will be seen that the atmospheric pressure within the chamber 35 4 will be maintained until the tripping operation, by the cup shaped packing members 30 and the check valve 20. The cylindrical body portion 3 of the cleanout tool, at a point below the packing cups 30, is provided with an exhaust aperture 40 31 which allows exhaust of air from the chamber 4 below the piston 8 when the device is lowered into the well and into the fluid therein, thereby preventing trapping of air below the piston, hence the forming of an air pocket is prevented. The 45 upper end of the coupling 1 terminates in a male member 32 which is received in the usual manner in the lower end of the female coupling 33.

50 Where there is very little water in the well, consequently very little hydrostatic pressure, the cleanout operation is obtained by a suction method.

55 Where it is necessary to use a suction, the extension member 34 may be used, the upper threaded end of which is threaded onto an end piece, which withstands the upward jarring action of the piston 38, however if the tool is working well hydrostatically, the piston can remain inactive and the suction portion then acts only as weight. The extension member 34 is provided with an elongated chamber 37, having a piston 38 slidably mounted therein and provided with a piston rod 39, the upper end of which terminates in a tool joint connector 22, adapted to be received by a drill string section so that when said section is axially reciprocated piston 38 60 will reciprocate therewith.

65 The piston 38 is provided with a passage 41 extending axially therethrough and through the piston rod 39 and terminating in transverse discharge apertures 21. In preparing the device for 70 operation, extension member 34 is screwed on the upper end of hydrostatic chamber at 32, the device cocked as shown in Figure 1 and run into the well. If suction is desired an up and down 75

movement is imparted to the piston rod 39, carrying the piston 38, which action causes the check valve 23 to close on the down strokes. On the up strokes of the piston 38 suction will be formed in chamber 37 as well as in the chamber 4, as the valve 20 will be seated and the hinged valve 23 unseated. This operation continues as long as is necessary to get a full load in the chambers 4 and 37. The débris in the bottom of the well will be sucked upwardly into the chamber 4, and trapped therein by the hinged valve 23. It will be noted that the lower end of the chamber 37 will be in communication with the chamber 4 through port 47 in the lower end of the extension section 34, at all times. It will be seen that a positive suction lifting system is provided in connection with the cleanout tool, and that the suction chamber 37 is free of débris.

In some cases it is necessary to agitate the débris in order to break loose the material to be moved, and in such case the scow bottom shown in Figures 4 and 5 is connected to the lower end of the device shown in Figures 1 and 2. In this case the cylindrical body 3 having the chamber 4 therein is not provided with a piston 8 but terminates at its lower end in a transversely extending V-shaped cutting and agitating tool 51, which is intermittently raised and lowered for the cutting operation. The tool 51 is provided with a transverse opening 52 therethrough and with a hinged valve 53, which is pivoted at 54, and has its free end resting on a removable screw 55. In this form as the tool is raised and lowered with the extension 34 connected thereto, the piston 38 will create a vacuum in the chambers 37 and 4, and will suck the dislodged and agitated material into the chamber 4 past the hinged valve 53. When the tool is removed, it will be noted that the same may be readily cleared by removing the screw 55 out of the path of the free end of the hinged valve 53, and this will allow the valve 53 to swing outwardly for the cleaning operation, which is a decided factor as it obviates the removal of the end of the device.

From the above it will be seen that a cleanout tool is provided for wells wherein the hydrostatic pressure may be utilized for forcing the débris from the bottom of the well into a cleanout tool, and if desired a suction system may be used when the hydrostatic pressure is low, or a dislodging tool where it is necessary to agitate the débris before the suction operation.

Means is provided between the chambers to receive a valve similar to that one which is used in the joint connector 22 if desired. This affords the means to pump a partial vacuum in the chambers before running the device into the well, where the hydrostatic pressure is small, and is only used with the hydrostatic unit.

The invention having been set forth what is claimed as new and useful is:

1. A well cleanout tool comprising an elongated member having a débris receiving chamber therein and adapted to receive and trap fluid under pressure, the lower end of said chamber being open to the well, a piston slidably mounted in said chamber, latching means for holding said piston in lowered position against fluid under pressure entering the lower end of the chamber and releasing means whereby said latching means will be released when the cleanout tool contacts the bottom of a well, whereby said piston may move upward under a hydrostatic pressure against atmospheric pressure within the chamber for a débris intaking operation.

2. A device as set forth in claim 1 including a closure valve for the lower end of the chamber below the piston and adapted to close after the piston moves upwardly for trapping débris in the chamber.

3. A device as set forth in claim 1 including means for allowing escape of air from the chamber above the piston as the piston moves upwardly.

4. A device as set forth in claim 1 including packing members carried by the piston for preventing passage of fluid pressure to the chamber and means for allowing escape of air to the well from the bottom of the chamber below the packing members.

5. The combination with a fluid pressure actuated cleanout tool comprising a piston slidably mounted in a casing chamber, said chamber being open at its lower end for communication with a well, of means for latching said piston in the lower end of the casing chamber against fluid pressure, said means comprising a shaft carried by the piston and extending beyond the lower end of the casing where it will engage the bottom of a well ahead of the tool casing, arms pivotally connected to the piston and extending downwardly towards the lower end of the chamber within the chamber, an annular channel in the inner periphery of the lower end of the chamber, headed members carried by said arms and disposed in said channel, an enlargement carried by the shaft and disposed between the headed members and maintaining the same in the channel, a slidable connection between said shaft and piston allowing limited axial freedom of movement of the shaft in relation to the piston, whereby the enlargement of the shaft upon initial movement of the shaft will move from between the headed members and release the arms, thereby allowing upward hydrostatic movement of the piston under fluid pressure from the well.

6. A device as set forth in claim 5 including a yieldable bumper carried by the upper end of the piston.

7. A device as set forth in claim 5 comprising a chamber in the piston, a head carried by the shaft and yieldable bumper means within the chamber of the piston and forming means for limiting and absorbing the shock of the initial upward movement of the shaft during the unlatching operation.

8. A device as set forth in claim 5 including an upwardly extending discharge passage carried by the cleanout tool and leading from the upper end of the chamber, and a check valve carried by said passage and forming means, whereby air under atmospheric pressure may be held in the chambers and fluid pressure from the well prevented from entering the chambers.

9. A device as set forth in claim 5 including a removable connector on the upper end of the tool and having a chamber therein, a check valve within said chamber and cooperating with a port leading to the chambers of the tool and allowing exhaust from the tool chambers and a port in the connector and forming means whereby fluid pressure within the well may enter the connector chamber and maintain the check valve closed until released by the greater fluid pressure forcing the piston upwardly.

10. The combination with a hydrostatically operated well cleanout tool having a chamber into which débris rushes in together with an upwardly moving piston in a chamber, latching means for holding said piston in lowered posi-

- tion, unlatching means for said latching means and extending below the lower end of the clean-out tool, of a removable lower end for said tool, said removable end carrying the latching means 5 in combination with the piston and a hinged valve carried by said removable end above the latching means within the end and forming means whereby the valve may be removed after the cleanout operation for removing débris from 10 the chamber of the tool.
11. A cleanout tool for wells comprising an elongated member having an upper chamber and a lower chamber, a port of communication between the upper chamber and the lower chamber 15 15, a reciprocating piston in the upper chamber and having an upwardly extending discharge port therethrough, a check valve in said discharge port and preventing downward flow between the discharge port and piston and forming means 20 whereby a suction may be formed in the upper and lower chambers upon the upward movement of the piston and the upper chamber, a piston in the lower chamber, means for latching the piston in the lower end of the lower chamber and 25 releasing the same, said reciprocating piston in the upper chamber forming means in combina-

tion with the check valve, whereby a suction may be formed in both chambers for a vacuum clean-out operation.

12. A device as set forth in claim 11 including an enlarged portion carried by the lower chamber 5 whereby when the lower piston is in raised position the vacuum action from the chambers may bypass the lower piston for an intaking operation below the lower piston.

13. A vacuum operated cleanout tool for wells 10 comprising an elongated member having upper and lower chambers, a port of communication between said chambers, a piston in the upper chamber, a piston in the lower chamber, said upper piston being reciprocally mounted, check 15 valve means whereby when the upper piston is reciprocated a vacuum will be formed in both chambers, means for latching the piston in the lower chamber against the action of the vacuum and means cooperating with the latching means 20 and adapted to be actuated by well engagement at the bottom thereof for releasing the lower piston and allowing its upward movement under the influence of the vacuum in the chambers.
